UNITED STATES PATENT OFFICE.

WILLIAM G. WILSON, OF WEST BRIGHTON, NEW YORK.

DESIGN FOR A PASTRY-LIFTER.

59,313.

Specification for Design.

Patented Oct. 4, 1921.

Application filed April 25, 1921. Serial No. 464,456. Term of patent 3½ years.

To all whom it may concern:

Be it known that I, WILLIAM G. WILSON, a citizen of the United States, residing at West Brighton, in the county of Richmond and State of New York, have invented a new, original, and ornamental Design for a Pastry-Lifter, of which the following is a specification, reference being had to the accompanying drawing, forming part thereof.

In the drawings:—

The figure is a perspective view of the pastry lifter.

I claim:—

The ornamental design for a pastry lifter, as shown.

WILLIAM G. WILSON.
